UNITED STATES PATENT OFFICE.

JOHN HARRINGTON, OF MOUNTAIN VIEW, CALIFORNIA; ALMENA C. HARRINGTON.
EXECUTRIX OF SAID JOHN HARRINGTON, DECEASED.

ENGINE.

1,100,974.

Specification of Letters Patent. Patented June 23, 1914.

Application filed June 3, 1912. Serial No. 701,184.

To all whom it may concern:

Be it known that I, JOHN HARRINGTON, a citizen of the United States, residing at Mountain View, in the county of Santa Clara and State of California, have invented new and useful Improvements in Engines, of which the following is a specification.

This invention relates to prime movers, 10 and particularly to internal combustion engines using crude oil or other liquid fuel.

The object of the present invention is to provide such a type of engine, with a two cycle operation.

15 The invention consists in the peculiar construction of the engine and its valve gear, whereby the engine is thoroughly scavenged to remove burnt gases, and in a special arrangement of the gas-controlling valve, and in the provision of means in the engine case for permitting the rapid inlet of a large quantity of compressed air into the combustion chamber and for water-cooling the exhaust valve.

25 It also comprises details of construction which will be more fully explained by reference to the accompanying drawing in which the figure is a central, vertical cross section of the engine.

30 A form of the engine is illustrated in the drawing and is shown as consisting of an engine casing, having an upper combustion and compression chamber 2, in which is reciprocable a piston 3 adapted, when in its lowermost position relative to the combustion cylinder 2, to run upon guiding ribs or bearings 4, of which a suitable number may be provided; there being formed between the sides of the ribs segmental air 35 passages or chambers 5 formed in an enlarged portion 6 of the casing. The chambers 5 communicate with a compression chamber 7 in the crank case 8 of the engine.

40 At one side of the crank case 8 is provided a suitable inlet valve 9, so that during the upward stroke of the piston 3 a charge of air will be drawn into the compression chamber 7, and which charge will be subsequently compressed during the 45 downward stroke of the piston 3.

In the present instance the stroke of the piston 3 is designed to be sufficient to uncover the upper ends of the air chambers 5 as the piston approaches its lowermost position, so that compressed air from the com-

pression chamber 7 will rush into the combustion chamber 2 of the engine; the area of the opening formed by the piston 3 at the upper ends of the chambers 5 between the ribs 4 preferably being considerable, so that a large volume of air from the compression chamber will rush directly around the upper end of the piston into the compression chamber; the inrushing air displacing the burnt gases which are permitted to escape through an annular or other suitable port 10 which is formed at the head of the cylinder 2.

45 For the purpose of opening and closing the annular port or other ports 10 at the proper period, I provide a balanced, annular, ring-like sleeve or valve 11, having a working fit with a seat 12 which is water cooled; the upper end of the valve 11 being adapted to cover or uncover the education port 10 formed on the cylinder head; the interior of the valve forming an initial combustion chamber surrounding the nozzle 17. Manifestly, the annular valve 11 may be reciprocated in proper time to open 50 or close the port 10 by any suitable form of mechanism. In the present instance I have shown the valve 11 provided with projecting trunnions 13, connected by rods 14 to and operable by a suitable cam structure 55 15, driven by any appropriate connections with the crank-shaft 16 of the engine. In this type of engine a hydrocarbon liquid fuel is introduced into the uppermost small part of the combustion chamber by a suitable spray or nozzle 17 fixed in the head of the cylinder 2; the fluid being injected through the nozzle under suitable pressure, and the nozzle 17 serving for the purpose of partially atomizing the fuel which is subsequently expanded by combustion, when ignited, in the combustion chamber 2. Manifestly any appropriate means may be employed for injecting the liquid fuel through the nozzle 17, and in the present instance a 60 force pump 18 is shown and operated by the cam-shaft 19.

65 For the purpose of obtaining efficient compression on the upward stroke of the piston 3 of the air which has been admitted 105 from the chamber 5 when the piston is in its lowermost position, an extension or protuberance 20 is formed on the upper end of the piston and this is adapted to approach the initial combustion chamber within the 110

valve 11 when the piston runs to its uppermost position.

The cycle of operation of the engine and the movement of the valve is as follows:

5 When the piston 3 is in its lowermost position, as shown, it has exposed the upper ends of the chambers 5 which communicate with the compression chamber 7, so that the air which has been compressed in the latter 10 chamber rushes into the combustion chamber 2; the burnt gases being expelled through the port or ports 10 in the head of the cylinder, and the ports having been opened somewhat before the upper end of the piston 15 3 crosses the upper ends of the air passages 5. In other words, the valve 11 is depressed as the upper end of the piston 3 approaches the edges of the air passages 5; this initial opening of the port 10 by the valve 11 permitting the gases in the combustion chamber 2 to escape so that the pressure thereof will be reduced to less than the pressure of air in the air chamber 7. Then as the piston 3 traverses the upper ends of the air 20 25 passages 5, the compressed air from the chamber 7 will rush into the combustion chamber 2 which is at this time opened to communicate with the atmosphere through the uncovered port 10.

30 On the subsequent upward stroke of the piston 3 its initial movement will cover the ends of the air passages 5, and for a certain remaining portion of the upward stroke of the piston the valve 11 will remain in 35 such a position as to leave the ports uncovered, so that all of the burnt gases in the upper part of the combustion chamber 2 will be expelled; when at a given time the valve 11 will be operated to cover the port 40 or ports 10, and thereafter during the remaining portion of the upward stroke of the piston 3 the air which was previously admitted over the piston, by uncovering the air passages 5, will be compressed. At approximately the time the piston 3 reaches 45 its uppermost limit of movement, a charge of liquid fuel will be injected through the spray device 17, by the pump 18, and the sprayed fuel will be ignited, and the force 50 of expansion will operate to drive the piston 3 downwardly until the latter approaches the upper ends of the air passages 5; when at a given time the valve 11 will be actuated to uncover the ports 10 so that the burnt 55 gases will, by their own pressure, partly escape through the ports 10, and subsequently as the piston 3 passes the ends of the air passages 5 the inrush of fresh air into the combustion chamber will further scavenge 60 the same.

The advantages of the present invention are that I am enabled to produce one power stroke for each revolution of the crank-shaft 16, and I am enabled to dispense with 65 a multiplicity of complex valves and their

respective operating mechanism, and employ in lieu thereof a simple sliding valve or sleeve having a small range of movement and which is positively driven so that it may be accurately timed for operation during the proper periods with relation to the movement of the piston of the engine.

By the provision of a suitable number of ribs or bearings 4 of such depth as to form comparatively large air chambers or passages 5 between their sides, I am enabled to introduce in the combustion chamber very quickly, a large volume of air compressed to such a degree as to effectually displace the burnt gases of the engine chamber 2, so that the latter is thoroughly scavenged, and at the same time a charge of fresh air is obtained in the combustion chamber, which charge is compressed to the requisite degree by the upward stroke of the piston 3. The efficiency of the engine may be increased by the provision of a lining 21 of some highly refractory material such, for instance, as corundum.

Combustion starts initially in the chamber 90 of the balanced valve 11, the interior surface of which retains its heat and is thus effective as an ignition device during operation.

Having thus described my invention, 95 what I claim and desire to secure by Letters Patent is—

1. An internal combustion engine comprising a cylinder, the upper portion of which is formed with a combustion chamber, a piston slideable in the combustion chamber, the lower portion of the cylinder being formed with a compressed air chamber, the upper edge of the chamber being so disposed that when the piston is in its lowermost position the upper edge of the chamber is in free communication with the combustion chamber, a plurality of ribs arranged within the lower portion of the cylinder and forming guides upon which the piston travels when it is in the lower portion of its stroke, the head of the cylinder being provided with a substantially annular projection open at its outer end to form an eduction port through which burnt gases are expelled by the inrush of compressed air admitted over the piston from the compressed air chamber when the piston is in its lowermost position, a sliding valve mounted in the head and adapted to cover and uncover said eduction port at a predetermined time with relation to the movement of the piston, and an inlet for the fuel located concentrically within said annular projection.

2. In an internal combustion engine, the 125 combination of a combustion chamber, an annular member projecting from the head of said chamber said member being open at its outer end to form an eduction port, a valve for closing said eduction port, an inlet 130

for fuel located within said annular member, a piston slidable in the combustion chamber, a projection on the piston adapted to enter the annular projection, an air compression chamber co-axial with said combustion chamber, and ports forming a connection between the two chambers when the piston is at the end of its working stroke.

In testimony whereof I have hereunto set my hand in the presence of two subscribing ¹⁰ witnesses.

JOHN HARRINGTON.
